COLLAPSIBLE BOX WITH END WALL LATCHES

Arthur L. Whiton, Evanston, Ill., assignor to Chicago Mill and Lumber Company, Chicago, Ill., a corporation of Delaware

Application April 8, 1935, Serial No. 15,171

4 Claims. (Cl. 217—12)

This invention relates to a collapsible box or a wire bound crate, the ends of which are closed by means of end walls or panels having spring latching members secured thereto for releasable engagement

5 engagement through slotted cleats secured to opposite walls of the main body portion of the box, said slotted cleats being provided with inclined grooves or kerfs in which the hook shaped ends of the spring latches are adapted to be lockingly

10 engaged to hold the end walls secured in place.

It is an object of this invention to provide a collapsible box or crate wherein the end panels or walls are provided with spring latching members for engagement through grooved cleats

15 forming parts of the end frames of the box.

Another object of the invention is to provide a knock-down box or crate of the wire bound type, wherein the ends of the crate are adapted to be closed by end panels having spring latching

20 means for resiliently locking the end walls in place.

It is also an object of this invention to provide a knock-down box wherein the end panels have metal latch hooks secured thereto for engagement 25 through the side wall cleats of the box to snap into latching grooves or kerfs to securely hold the end walls in closed position within the body of the collapsible box.

It is furthermore an object of this invention 30 to provide spring latching members for the end walls of a knock-down crate to facilitate rapid and efficient securing of the end panels of a knock-down box in position to close the ends of a box body.

35 It is an important object of this invention to provide a collapsible crate or knock-down box with end closure panels having metal latching hooks secured thereto for engagement through grooved cleats forming a part of the body of the box.

Other and further important objects of this invention will be apparent from the disclosures in the specification and the accompanying drawing.

45 The invention (in a preferred form) is illustrated in the drawing and hereinafter more fully described.

On the drawing:

Figure 1 is a perspective view of a knock-down 50 box having end panels equipped with spring latching means embodying the principles of this invention.

Figure 2 is an enlarged fragmentary horizontal 55 sectional view taken on line II—II of Figure 1.

Figure 3 is an enlarged fragmentary vertical 60 sectional view taken on line III—III of Figure 2.

Figure 4 is an enlarged fragmentary sectional view through one corner of the box taken on line IV—IV of Figure 1 illustrating a fragmentary portion of an end panel in release position in full

lines and showing the outward path of movement of the end panel in dotted lines with the latch hooks only partly engaged through the cleat grooves.

Figure 5 is an enlarged fragmentary detail section taken on line V—V of Figure 1, illustrating the latching means in locking position connected to an end frame cleat and illustrating the end panel in its final closed position.

Figure 6 is a fragmentary sectional view similar to Figure 2 illustrating a modified form of latching means for holding an end panel locked in position to close an end of the knock-down box or crate.

As shown on the drawing:

The improved knock-down crate while illustrated as being of the wire bound type may be of any other desired type having end walls or panels for closing the ends of the box. While the box is illustrated with a closure top or cover 20 the present invention is equally applicable for boxes open at the top.

In the present showing of the invention the wire-bound knock-down box or crate comprises a body portion constructed of a top or cover 25 panel 1, a rear or side panel 2, a bottom or floor panel 3, and a front or side panel 4.

The four panels or walls 1 to 4 are constructed of wood or other suitable material and are connected in the form of a wire bound mat by means 30 of binding wires 5 attached transversely across the exterior surfaces of the panels by means of staples 6 or the like.

Secured transversely across the inner surface of the end margins of the top or cover panel 35 1 are end cleats 7 provided with beveled ends. The rear or side wall 2 is provided with transversely disposed cleats 8 which are secured transversely across the end margins of the panel 2. The ends of the cleats 8 are cut to provide beveled 40 end surfaces. The bottom or floor panel 3 has end cleats 9 secured transversely across the inner surfaces of the end margins thereof, and the ends of said cleats 9 are also cut to provide beveled end surfaces. Secured transversely across the in- 45 inner surface of the end margins of the front or side panels 4 are cleats 10, the ends of which are beveled. When the box is in its assembled form the end cleats 7, 8, 9 and 10 are positioned with the beveled ends thereof abutting against one an- 50 other to form end frames for the box. As illustrated in Figure 1 the ends of the binding wires 5 are bent over to provide locking loops 11 adapted to be interlocked to hold the cover 1 in a closed position.

Each of the front and back or side wall cleats 8 and 10 is provided with a transverse slot or passage 12 in substantially the middle portion of the outer side wall thereof. The outer sides of the slots 12 are closed by the respective back wall 60

2 and the front wall 4. The front ends of the slots 12 communicate with diagonal kerfs or grooves 13 which are provided in the outer margins of the front surfaces of the cleats 8 and 10 and form tapered latching beads or ribs 14, as clearly illustrated in Figure 4.

Each end of the body portion of the box or crate is adapted to be closed by means of an end panel or end wall 15. Secured across the outer surface of each end margin of each of the end walls 15 is a transverse reinforcing strip or board 16 held in place by means of staples or other suitable fastening devices. The reinforcing strips 16 are constructed of wood or other suitable material and are offset from the ends of the end walls a distance equal substantially that of the depth of the grooves 12. Secured in place by each of the reinforcing or retaining strips or slats 16 is a metal latching plate or strap 17 which is clamped between the outer surface of the end wall and the inner surface of the reinforcing strip 16. The inner end of the metal latching strap 17 is bent outwardly to form a retaining flange 18 which seats tightly against the inner longitudinal edge of the reinforcing strip 16. Normally the outer end of each of the metal latching straps 17 projects outwardly parallel to the plane of the end wall to facilitate stacking of the end walls when the box is in knock-down or collapsed position. When the end walls are to be engaged in position, the outer end of each of the latching straps 17 is bent outwardly at substantially right angles to form a spring latch 19, the outer end of which is deflected inwardly and downwardly to conform a locking hook flange 20.

To close an end of the body portion of the box, an end wall 15 is engaged transversely within the body of the box and is then pushed outwardly from the full line position of Figure 4 toward the dotted line position of said figure permitting the spring latch members 19 to project into the grooves 12 of the cleats 8 and 10. As the spring latch members 19 move through the slots 12 the hook portions 20 act to deflect the spring latch members outwardly so that when the wall reaches its outermost position with the reinforcing strip 16 in contact with the inner surfaces of the cleats 8 and 10, the hook latching flanges 20 snap or spring inwardly over the locking beads 21 or ribs 14 to securely hold the end wall locked in position.

After the two end walls 15 are locked in position by means of the spring latch members 19-20 the top 1 is closed and the looped ends 11 of the binding wires 5 are interlocked as illustrated in Figure 1 to hold the box locked in its assembled form.

With applicant's improved collapsible or knock-down box the wire bound mat consisting of the top, bottom and side walls connected by means of the binding wires may be quickly bent into position to form the main portion of the body of the box after which the end panels or walls 15 are moved into position to allow the spring latching members 19-20 to engage through the side wall cleats 8 and 10 to permit the hooked latching flanges 20 to snap into position over the latching beads or ribs 14, thereby completing the formation of the box. The box may now be filled and the cover or top closed and locked by means of the interfitting of the looped wires 11. In case it is desired, the box after being used may be knocked down by first opening the top and then releasing the spring latch members 19-20 from

engagement with the inclined surfaces of the latching beads 14, thereby allowing the end walls to be moved inwardly and out of the body portion of the box after which the wire bound mat may be straightened out or folded in collapsed position with the removed end walls ready to be piled thereon.

Figure 6 of the drawing illustrates a fragmentary portion of a modified form of a collapsible box wherein end panels or walls 21 are provided with a metal strip or band 22 which is laid across the middle portion of the inner face of the wall. Transverse wooden strips or slats 23 are secured across the end margins of the inner face of the end wall 21 by means of staples or other suitable fastening devices. The wooden strips 23 serve to hold the metal strip 22 in position. The ends of the metal strip 22 project beyond the ends of the end wall 21 and are bent outwardly at substantially right angles to form resilient latching members 24, the outer ends of which are bent inwardly at a slant to provide hooked latching flanges 25. The spring latching members 24-25 are adapted to be projected through the slots 12 of the side wall cleats to releasably hold the end walls 21 in position to close the open ends of the box body.

It will of course be understood that various details of construction may be varied through a wide range without departing from the principles of this invention, and it is therefore not the purpose to limit the patent granted hereon otherwise than necessitated by the scope of the appended claims.

I claim as my invention:

1. A collapsible box including in combination a body including end frame cleats having slots and grooves therein, a pair of end walls, and hooked metal strap springs projecting from the end walls into said slots so as not to project beyond the ends of the box to lockingly engage in the cleat grooves to hold the end walls locked in place.

2. A collapsible box comprising a wire bound mat including wall sections having cleats secured thereto, said cleats having slots therein, locking beads formed on the cleats, end walls, and hooked spring latch members on the end walls engaged in the slots and hooked over the locking beads within the ends of the box to hold the end walls in place.

3. A collapsible box comprising a body including side walls, cleats secured across the ends of the side walls and having transverse slots and inclined longitudinal grooves therein, a pair of end walls, latch means on the end walls for projection part way through said slots to spring into locking engagement in said grooves to hold the end walls locked in position to close the ends of said body, said latch means having the outer ends thereof seated in said grooves so as not to project beyond the ends of the box.

4. A collapsible box including in combination a body section having cleats secured thereto to form end frames, each of said end frames having two opposite cleats thereof provided with a transverse slot in one surface thereof and a longitudinal inclined groove in an adjacent surface, a pair of end walls, and hook-shaped spring latching means secured to each of the end walls and projectable through the cleat slots to lockingly hook into the inclined cleat grooves to secure the end walls in place.

ARTHUR L. WHITON.
